UNITED STATES PATENT OFFICE.

JOHN E. CAVANAGH, OF CLOQUET, MINNESOTA.

WATER-CIRCULATING SYSTEM FOR STEAM-BOILERS.

SPECIFICATION forming part of Letters Patent No. 695,088, dated March 11, 1902.

Application filed April 13, 1901. Serial No. 55,611. (No model.)

To all whom it may concern:

Be it known that I, JOHN E. CAVANAGH, a citizen of the United States, residing at Cloquet, in the county of Carlton and State of Minnesota, have invented certain new and useful Improvements in Water-Circulating Systems of Steam-Boilers; and I do hereby declare the following to be a full, clear, and exact description of the invention, such as will enable others skilled in the art to which it appertains to make and use the same.

My invention relates to steam-boilers, and is particularly directed to the improvement of the circulating system or connections there-

for. The principal object of my invention is to provide circulating connections which will direct the circulating water back into the boiler in such manner that a spiral motion will be given to the water within the boiler and around the generating-flues thereof. This spiral motion of the water is preferably started at one end of the boiler and continued to the opposite end thereof. Under this motion the temperature of the water throughout the boiler is kept very nearly even and an approximate equal amount of moving water is brought into contact with each generating-flue. Furthermore, by this same action or spiral movement of the water all mud or foreign material contained in the water will be kept stirred up and prevented from settling within the boiler, from which it follows that such sediment will be precipitated only within the mud-drum or other receptacle of the circulating connections which answers as a depository for such mud or sediment.

My invention is illustrated in the accompanying drawings, wherein like characters indicate like parts throughout the several views.

Figure 1 is a view, partly in side elevation and partly in vertical section, showing an ordinary horizontal boiler having elected thereunto a circulating system of connections arranged in accordance with my invention. Fig. 2 is a vertical section taken approximately on the irregular line $x^2 x^2$ of Fig. 1, some parts being broken away. Fig. 3 is a view corresponding to Fig. 1, but illustrating a slightly-modified construction. Fig. 4 is a view corresponding to Figs. 1 and 3, but illus-

trating a construction in which a mud-drum is used in the circulating connections and illustrating also certain other novel features 55 of my invention; and Fig. 5 is a transverse vertical section taken approximately on the irregular line $x^5 x^5$.

In all the constructions described numeral 1 indicates the body of the boiler, the numeral 2 the flues, the numeral 3 the smoke-box, and the numeral 4 the smoke-stack of an ordinary horizontal boiler. The boiler is shown as supported and incased in the ordinary way by masonry, (indicated in its entirety by the 65 numeral 5.)

Numeral 6 indicates the fire-box grate, the numeral 7 the front wall of the fire-box, and the numeral 8 the rear wall of the said fire-box. The said wall 8 terminates below the 70 bottom of the boiler 1 and serves to deflect upward the products of combustion as they pass from the fire-box or combustion-chamber 9 to the rearwardly-extended combustion-chamber 10.

In the construction illustrated in Figs. 1 and 2 the water circulates downward from the boiler through a downflow-pipe a , which is connected, as shown, by a T-head a' to the rear end of a horizontally-extended pipe a^3 , 80 to the forward end of which pipe another T-head a^3 is shown as secured. The downflow-pipe a opens centrally from the lowermost and rearmost portion of the said boiler, and an exhaust or discharge pipe a^4 , having a 85 valve a^5 , opens from the T-head a' and leads to a suitable point of discharge. A removable cup-like section or cap a^6 normally closes the lower end of the T-head a^3 . As best shown in Fig. 1, the T-head a^3 is located forward of the wall 8 and is exposed to the direct heat of the combustion within the fire-box. As best shown in Fig. 2, a two-pronged circulating-pipe b extends upward from the T-head a^3 , the same, as shown, being connected 95 therewith by a suitable coupling b' . From the upper end of each prong or pipe b a circulating-pipe b^3 extends forward of the front end of flue-sheet 1^a of the boiler. From the forward end of one of the circulating-pipes 100 b^2 (shown from the right-hand member as viewed in Fig. 2) a pair of slightly-reduced pipe-sections $c c'$ open into the boiler, on the right-hand side thereof, through the forward

flue-sheet 1^a. From the forward end of the other circulating-pipe b² a single circulating-pipe c² also opens into the right-hand side of the boiler, as viewed in Fig. 2, and through 5 the said flue-sheet a'. Preferably the pipes c, c', and c² should open through the flue-sheet 1^a at points where they will not cause the removal of a flue or flues. Also the pipe c² is 10 advisably of such size that it will have a conductivity equal or approximately equal to the two pipes c and c' taken together.

The construction illustrated in Fig. 3 is the same as that illustrated in Figs. 1 and 2, except that the T-coupling a³ is located to the 15 rear of the wall 8 and is connected with the elbow of the discharge-pipe a⁴ by means of a depending settling leg or tube a⁷ and a horizontal pipe a⁸.

In the construction illustrated in Figs. 4 20 and 5 the discharge-pipe a⁴ is omitted, and to the forward end of the horizontally-extended pipe a² a transversely-extended settling-drum f is secured, as shown by coupling f'. The sediment from the drum f is adapted to be 25 drawn off through a pipe f², having a valve f³, which is normally closed. In this arrangement the drum f is connected to the forward end of the boiler 1 by means of a pair of pipes g, g', which open through one side of the 30 boiler, and by a third pipe g², which opens through the other side of the boiler. With this construction twice as much water will be introduced at one side of the boiler as there will at the other side. Hence the water in 35 the boiler will be circulated with a spiral motion, but not to the same extent as in the construction wherein all of the circulating water is returned into the boiler at a common side thereof.

40 With the circulating connections described the circulating water is in the one instance returned to the front end of the boiler and delivered entirely at one side thereof, while in the other instance it is delivered on both sides; but an excessive amount is delivered 45 on the one side. The same principle is involved in both arrangements, although the best results are obtained by delivering the water entirely to one side. In both cases 50 the water is drawn off from the other end of the boiler at the bottom and central portion thereof. The hot water delivered at one side of the boiler tends to rapidly rise, and if delivered on both sides the water at that side 55 which receives the greatest amount of hot water will rise with the greatest force. This action of the water, due, of course, to the law of convection and the returning cooler-currents, will produce a rotary motion of the 60 water, and as the water is constantly drawn toward the opposite end of the boiler it will take a spiral motion. The expression "delivering in excess at one side" is herein used in a generic sense to indicate delivering the 65 water entirely at one side or delivering the water at both sides, but a materially greater amount at one side than at the other.

In the several constructions illustrated the lower horizontal pipes a² are covered by a layer of fire-brick k or similar fireproof material. This layer of brick k protects the pipe a² from the intense heat from the combustion within the overlying chamber 10 and prevents the water from becoming intensely heated before it has reached the forward end of the 70 said pipe a², at which point it is free to pass upward and back to the boiler. In this way an exceedingly rapid circulation is insured.

As another feature of my invention the cold water from the injector or other means 80 of supply is delivered by a pipe p, which terminates within the boiler in direct vertical line with the downflow-pipe for the circulating water, which downflow-pipe in the several constructions illustrated is a short pipe 85 a. This inlet-pipe p is provided with a valve p', and at its depending end it is shown as provided with a slightly-contracted discharge-nozzle p², while in its sides it is shown as provided with several lateral openings p³. As 90 the water introduced through the pipe p is very cold as compared with the water in the boiler, it will of course upon its introduction into the boiler be rapidly precipitated to the bottom of the same, and as it is thus precipitated directly over the downflow-pipe a the downward flow of the circulating water is thereby accelerated. In all of the constructions illustrated the downflow flow of the cold water is through a single large pipe, and 95 the return flow of the heated water is through 100 the plurality of relatively small pipes.

In the construction shown in Figs. 1 and 2 the mud or sediment in the water will be precipitated to a considerable extent in the outlet-pipe a⁴ and also within the cup or cap a⁶ 105 and after these are filled, or nearly so, within the horizontal pipe a². Hence it is evident that with this construction the said parts a², a⁴, and a⁶ must be cleaned quite frequently. 110 This, however, may be very readily done by opening the valve a⁵ and blowing out the pipes a³ and a⁴ and by removing the cup a⁶ to clean the same.

The pipes a², a⁴, a⁷, and a⁸ (illustrated in 115 Fig. 3) may all be cleaned by blowing them out while the valve a⁵ is open.

As already indicated in the construction illustrated in Figs. 4 and 5, the mud-drum may be cleaned out by opening the valve f³. 120

It will of course be understood that my invention is capable of many modifications other than those herein illustrated. The means for producing a spiral or circular motion of the water within the boiler I consider, 125 broadly, new.

What I claim, and desire to secure by Letters Patent of the United States, is as follows:

1. The combination with a horizontal boiler, 130 of circulating connections therefor receiving the water from the lower portion of one end of the boiler and delivering the same back into the other end of the boiler, an excessive amount of water being delivered at one side

of the boiler and above the point of outlet from the other end of said boiler.

2. The combination with a horizontal boiler having horizontally-extended flues, of circulating connections therefor, receiving the water from the lower central portion of one end of the boiler and delivering the same back into the other end of the boiler, entirely at one side thereof, and above the point of out-

let from the other end of the boiler, substantially as described.

In testimony whereof I affix my signature in presence of two witnesses.

JOHN E. CAVANAGH.
